UNITED STATES PATENT OFFICE.

PETER R. MEADVILLE, OF LAWTON, OKLAHOMA.

DERRICK ELEVATOR.

Application filed October 1, 1927. Serial No. 223,425.

It is necessary, in oil fields, and as a matter of fact in other places, where derricks are erected for the attendant or mechanic to frequently climb the derrick for repairs and for other purposes. To accomplish this the derricks are provided with ladders. In oil fields especially these ladders become saturated with oil rendering the climbing thereof difficult and dangerous. Also in the winter time the derricks become icy, which adds to the danger of the person ascending and descending the same.

It may, therefore, be considered the primary object of this invention to provide a derrick with an elevator in the nature of a man-lift which is designed to supplant the usual ladder and which is of a construction and arrangement whereby a person or persons may easily, quickly and safely ascend or descend the derrick, there being means connected with the car of the elevator for engaging the derrick to hold the said car at different stages on the derrick frame.

A still further object is the provision of a man-lift in the nature of an elevator for derricks in which a car is arranged for vertical movement on one side of a derrick and the weight of the car is counter-balanced so that only a small expenditure of physical exertion will be required in the ascent or descent of the car.

A still further object is the provision of a man-lift for derrick frames that shall be of an extremely simple construction and which may be readily, easily and quickly fixed to the side of the derrick frame and further one which will fully protect the occupant of the car against usual dangers and permit of the ready ascent and descent of the car.

To the attainment of the foregoing the invention consists in certain other novel features of construction, combination and operative association of parts, a satisfactory embodiment of which is disclosed by the accompanying drawings which form part of this application.

In the drawings:

Figure 1 is a side elevation of a derrick frame provided with the improvement.

Figure 2 is an enlarged central longitudinal sectional view through the improvement as arranged on the derrick frame.

Figure 3 is a sectional view approximately on the line 3—3 of Figure 2.

Figure 4 is a detail sectional view approximately on the line 4—4 of Figure 2.

In the drawings, the numeral 1 designates a derrick frame of the usual construction. For distinction the top platform of the frame is indicated by the numeral 2. Secured to the under face of this platform and likewise secured to the sides of the derrick frame there is the track of my improvement. The track comprises two spaced vertically disposed rails 3—3. Each of these rails is in the nature of an eye beam, the inner flanges of which being secured to the derrick frame. Of course, the track is of a length equaling the height of the derrick frame.

Fixedly secured to the top platform 2 of the derrick frame, centrally with respect to the rails of the track, there is a pulley or sheave wheel 4 around which is trained a cable 5 and one end of this cable is secured to the top of a box or basket 6 which is arranged for movement between the inner or confronting channels of the I beam rails 3. The second end of the cable 5 is fixedly secured to the inner wall of the car 7. The car is preferably in the nature of an open member of substantially rectangular formation and has secured to its front and to its sides, adjacent to the top and bottom of the said car, substantially U-shaped metal bars 8, respectively. The bars 8 project a suitable distance beyond the inner face or rear face of the car and the said bars have their free ends bent angularly toward each other to provide short shafts or trunnions for rollers 9 that are received in the usual channels of the I beam rails 3.

Fixedly secured to the bottom of the box-like member or basket 6 there is a second cable 10. This cable is trained to a sheave or pulley wheel 11 that has its shaft 12 journaled in suitable bearings in the bifurcated portion of a support 13 that is fixedly secured to the floor at the outer side of the derrick and the end of the cable 10 is fixedly secured to the rear wall, adjacent to the bottom of the car 7.

Swivelly connected, as at 14, to one side of the car there is a hook 15 and this hook is designed to be swung over any portion of the derrick frame for holding the car at desired elevations thereon.

The box 6 and the car 7 are counter-balanced. As the car 7 is of a comparatively heavy structure weights 16 are placed in the box 6. Assuming that the car has made its full descent and the box 6 is fully elevated, the operator places himself in the car and

grasping the cable 10 exerts a downward pull thereon, which, of course, will lower the box as the car ascends. The car and box will meet at approximately the center of the derrick. It is to be noted that the box 6 is of an open construction, so that the operator may first grasp the bottom of the box to cause the car 7 to make a further ascension. The operator may then grasp the top 10 of the box, causing the latter to make a further descent and the car a further ascension. When he is in position to do so, the portion of the cable 5 trained over the sheave wheel 4 and connected to the top of the box 6 is 15 grasped and a pull is now exerted upon this portion of the cable 5, and by grasping the said portion of the said cable at different elevations, the car will make its full ascension. As the car and the box are counter- 20 balanced the operator, after making repairs or attaching parts to the top of the derrick, when he again places his weight in the car 7 it will automatically descend. The rapidity of the downward movement of the car 7 is 25 regulated by the operator grasping the part of the cable 5 which is attached to the box 6, thereafter grasping the box 6 when the car is in a line therewith and thereafter grasping the cable 10 at different parts 30 thereof and thereby steadyng the descent of the car 7.

The simplicity of the construction and the advantages thereof will it is thought be apparent to those skilled in the art to 35 which such invention relates, but I desire it understood that I do not wish to be restricted to the precise details herein set forth and, therefore, hold myself entitled to make such changes therefrom as fairly 40 fall within the scope of what I claim.

Having described the invention, I claim:

1. The combination with a derrick frame, of a vertical track secured on one side thereof and comprising a pair of spaced rails each in the nature of an I beam, a car having 45 rollers which are journaled in the outer channels of the I beam, a box designed for the reception of weights and which is arranged for movement between the inner channels of the I beams, grooved wheels 50 centrally fixed at the top and at the bottom of the frame between the rails of the car, a cable secured to the top of the car trained over the upper grooved wheel and secured to the top of the weight carrying box, a 55 second cable secured to the bottom of the weight carrying box, trained over the lower grooved wheel and secured to the car.

2. The combination with a derrick frame, of a man-lift therefor including a vertically 60 disposed track secured to one side of the derrick frame comprising a pair of spaced rails, of I beam construction, a weight carrying box movable in the inner channels of the rails, a car comprising an open member 65 having substantially U-shaped spaced rods secured thereon and extending rearwardly therefrom and having their ends inturned to provide trunnions, rollers journaled on the trunnions and received in the outer grooves 70 of the rails, upper and lower grooved wheels fixedly secured between the rails of the track, a cable fixedly secured to the car, trained over the upper grooved wheel and fixed to the top of the box and a second cable fixed to the bottom of the box, trained to the lower wheel and fixedly secured to the car.

In testimony whereof I affix my signature.

PETER R. MEADVILLE.
